5 Claims. (Cl. 103—103)

The present invention relates to centrifugal pumps and in particular centrifugal pumps for handling fluid comprising a mixture of liquid and gas as well as such fluids containing solids.

It is well known that the quantity of liquid delivered by a centrifugal pump varies according to the blade form and shape of the casing. It is also known that with present pumps the liquid lies close on the back of the blade while the other side of the blade is covered with air or gas which has either been forced out of solution or was present in the pump. This air or gas forms a cushion which has a detrimental effect on the pumping efficiency. Generally, such pumps cannot be employed without auxiliary equipment for the pumping of large heads as the liquid column is interrupted by the air. Earlier centrifugal pumps had great difficulty and in some cases were completely unable to deliver liquids containing froth or air as the air separated and formed a cushion which interrupted the flow of the liquid. The method employed in this invention removes these disadvantages by ensuring that approximately the same homogeneous liquid-gas mixture is generated in all the channels between the blade walls of the wheel and that an injector-type suction effect is produced inside these channels.

In a centrifugal pump to carry out this method, grooves are provided on opposite walls forming the passage between the blades, these grooves giving successive sudden increases in the cross section of the passage.

In the accompanying drawings, selected embodiments of the object of the invention are illustrated by way of example. In the drawings:

Fig. 1 is a partial axial section of a centrifugal pump in accordance with the invention;

Fig. 2 is a cross section taken approximately on the line 2—2 in Fig. 1;

Figs. 3 and 4 are fragmentary axial sections illustrating other embodiments;

Figs. 5 and 6 are cross sections similar to Fig. 2 but illustrating other embodiments.

The embodiment of the invention shown in Figs. 1 and 2 comprises two coaxial discs 1 and 2 which are spaced from one another. The disc 1 has a hub portion 6 which, as illustrated in Fig. 2, is mounted on a shaft 7, the shaft being omitted in Fig. 1. The disc 2 has a hub portion 6a in which there is provided a central opening 8 that provides an inlet passage for the pump. Between the discs 1 and 2, there are provided a plurality of outwardly radiating blades or vanes 4 which connect the two discs. The circumferentially spaced blades 4, together with the axially spaced discs 1 and 2, define a plurality of fluid channels 3 communicating with, and radiating out from, the inlet opening 8.

Opposite surfaces of the channels 3 formed by the discs 1 and 2 are provided with a series of grooves 5 which are approximately concentric with the discs and hence extend transversely to the direction of fluid flow out through the channels 3. The grooves 5 are of saw-tooth configuration, being defined by the intersection of annular

2

surfaces 5a approximately perpendicular to the direction of the flow of fluid in said channels 3 and annular surfaces 5b which are inclined axially inwardly toward the opposite disc and radially outwardly. The intersection of the surfaces 5a and 5b forms circumferentially extending ridges 5c which alternate with the grooves 5, as shown. Individual grooves 5 in the two discs are disposed approximately opposite one another and provide sudden increases in the channel cross section. This configuration of the wall surfaces of the channels 3 produces turbulence in the fluid so that a fluid comprising liquid and gas is maintained in a mixed state. Separation of the liquid and gas phases and the accumulation of gas along the wall faces of the channels are thereby inhibited. It has been found that pumps in accordance with the invention can be operated with a higher suction head than centrifugal pumps of conventional design, even though the fluid contains a substantial amount of gas.

Another embodiment of the invention is illustrated in Fig. 3 in which corresponding parts are designated by the same reference numerals as in Fig. 1 with the addition of 10. The pump comprises a non-rotating wall disc 11 and a rotating hub 16 carrying a plurality of circumferentially spaced blades 14 and a disc 12 having a central portion 16a in which there is formed an inlet passage 18. The blades or vanes 14, together with the non-rotating disc 11 and rotating disc 12, define a plurality of fluid channels 13 radiating out from the inlet passage 18. The discs 11 and 12 are provided with grooves 15 which correspond to the grooves 5 of Fig. 1 and are of saw-tooth cross section. The grooves 15 extend in an approximately circumferential direction so as to be disposed transversely to the direction of flow of fluid in the channels 13. The edges of the vanes 14 adjacent the disc 11 are of saw-tooth configuration so as to fit into the grooves 15. Between the discs 11 and 12, there is provided a partition ring 19 which is carried by the vanes 14 and extends inwardly from the peripheries of the discs 11 and 12. The partition 19 thus divides the outlet portions of each of the channels 3 into two parts. More than one ring could, of course, be provided so that each of the channels is divided into a corresponding number of parts. Grooves 15' of saw-tooth cross section, corresponding to the grooves 15, are provided on one or both faces of the partition ring 19.

A third embodiment of the invention is illustrated in Fig. 4 in which corresponding parts are designated by the same reference numerals as in Fig. 1 with the addition of 20. In this embodiment, a disc 21 and circumferentially spaced blades or vanes 24 rotate with a hub 26 while a second disc 22 having a central opening 28 formed in a hub portion 26a is stationary. The discs 21 and 22 are provided on their inner faces with oppositely disposed grooves or recesses 25 which are of saw-tooth cross section and extend transversely to the direction of flow of fluid outwardly through channels 23 defined by the discs 21 and 22 and the vanes 24. The edges of the vanes 24 adjacent the stationary disc 22 are of saw-tooth shape so as to fit into the grooves 25.

Another modification is illustrated in Fig. 5 which corresponds in general to Fig. 2 and in which corresponding parts are designated by the same reference numerals as in Fig. 2 with the addition of 30. As in the embodiments described above, the pump comprises a pair of axially spaced discs, one of which is indicated at 31, the other not being shown in this figure. A hub portion 36 is keyed on a shaft 37. A plurality of circumferentially spaced vanes 34 are provided between the two discs. The inner faces of the axially spaced discs are provided with circumferentially extending grooves 35 which are of saw-tooth cross section, as illustrated in Fig. 1. Similar grooves 35' are provided on the vanes 34.

A further modification is illustrated in Fig. 6 which corresponds in general to Fig. 2 and in which corresponding parts have been designated by the same reference numerals as in Fig. 2 with the addition of 40. The embodiment of Fig. 6 is similar to those described above and comprises axially spaced discs one of which is indicated at 41 while the other is not shown. A hub 46 is mounted on a shaft 47 and blades 44 are provided between the two discs. The circumferentially spaced blades or vanes 44, together with the axially spaced discs, define a plurality of outwardly radiating channels 43. Additional blades 49 extend inwardly from the peripheries of the discs and divide the outlet portions of the channels 43 into two parts. The inner faces of the disc 41 and the axially spaced opposite disc (not shown) are provided with grooves 45 which are of saw-tooth cross section like the corresponding grooves of the embodiments described above. The grooves need not be strictly concentric with the discs so long as they extend transversely to the direction of flow of fluid in the channels 43. The vanes 44 and 49 are provided with similar saw-tooth grooves 45' which likewise extend transversely to the direction of fluid flow.

What we claim is:

1. In a centrifugal pump for handling fluids comprising a mixture of liquid and gas, said pump having a pair of annular concentric axially spaced walls having opposite inner faces cooperating together to form a pumping chamber, one of said walls having a central inlet opening to said pumping chamber and at least one of said walls being rotatable, a plurality of circumferentially spaced vanes extending axially from one of said walls to the other and dividing said pumping chamber into a plurality of fluid channels communicating with and radiating out from said inlet opening, said vanes being fixed to said rotating wall to rotate therewith, the opposite inner faces of said walls having a series of radially spaced concentric annular grooves, the grooves in one face having the same radial spacing as the grooves in the opposite face so that the grooves in opposite wall faces form concentric pairs, each of said grooves being of saw-tooth cross section and formed by a pair of intersecting surfaces, one of said surfaces extending axially from the bottom of said groove toward the opposite one of said walls and the other of said surfaces extending radially outwardly from the bottom of said groove and being inclined axially inwardly toward the opposite one of said walls, said concentric pairs of grooves cooperating with one another to form successive gradual reductions and sudden increases in said fluid channels to produce a pumping action to keep said liquid and gas mixed and prevent accumulation of gas in said pumping chamber.

2. A centrifugal pump according to claim 1, in which both of said walls rotate together and said vanes are fixed to both of said walls.

3. A centrifugal pump according to claim 1, in which one only of said walls rotates, the other being stationary, and in which said vanes are fixed to said rotating wall and extend into the grooves of said stationary wall.

4. In a centrifugal pump for handling fluids comprising a mixture of liquid and gas, said pump having a pair of annular concentric axially spaced walls having opposite inner faces cooperating together to form a pumping chamber, one of said walls having a central inlet opening to said pumping chamber and at least one of said walls being rotatable, a plurality of circumferentially spaced vanes extending axially from one of said walls to the other and dividing said pumping chamber into a plurality of fluid channels communicating with and radiating out from said inlet opening, said vanes being fixed to said rotating wall to rotate therewith and having opposite axially extending faces, the opposite inner faces of said walls having a series of radially spaced concentric annular grooves, the grooves in one face having the same radial spacing as the grooves in the opposite face so that

the grooves in opposite wall faces form concentric pairs, each of said grooves being of saw-tooth cross section and formed by a pair of intersecting surfaces, one of said surfaces extending axially from the bottom of said groove toward the opposite one of said walls and the other of said surfaces extending radially outwardly from the bottom of said groove and being inclined axially inwardly toward the opposite one of said walls, said concentric pairs of grooves cooperating with one another to form successive gradual reductions and sudden increases in said fluid channels to produce a pumping action to keep said liquid and gas mixed and prevent accumulation of gas in said pumping chamber, like grooves being formed in at least one of said faces of each of said vanes and extending axially between the opposite inner faces of said walls, said grooves in the vanes cooperating with said grooves in said walls to keep said liquid and gas mixed.

5. In a centrifugal pump for handling fluids comprising a mixture of liquid and gas, said pump having a pair of annular concentric axially spaced walls having opposite inner faces cooperating together to form a pumping chamber, one of said walls having a central inlet opening to said pumping chamber and at least one of said walls being rotatable, a plurality of circumferentially spaced vanes extending axially from one of said walls to the other and dividing said pumping chamber into a plurality of fluid channels communicating with and radiating out from said inlet opening, said vanes being fixed to said rotating wall to rotate therewith, an annular partition disposed between said walls and carried by said vanes, said partition extending radially inwardly from the outer ends of said channels part way to said inlet opening and thereby dividing the outer portion of each of said channels into two parts, the opposite inner faces of said walls having a series of radially spaced concentric annular grooves, the grooves in one face having the same radial spacing as the grooves in the opposite face so that the grooves in opposite wall faces form concentric pairs, each of said grooves being of saw-tooth cross section and formed by a pair of intersecting surfaces, one of said surfaces extending axially from the bottom of said groove toward the opposite one of said walls and the other of said surfaces extending radially outwardly from the bottom of said groove and being inclined axially inwardly toward the opposite one of said walls, said concentric pairs of grooves cooperating with one another to form successive gradual reductions and sudden increases in said fluid channels to produce a pumping action to keep said liquid and gas mixed and prevent accumulation of gas in said pumping chamber, the opposite faces of said partition being likewise formed with a series of concentric annular grooves corresponding to said grooves in said wall faces and of like cross section and arrangement, said grooves in said partition faces cooperating with said grooves in said wall faces to keep said liquid and gas mixed.
